UNITED STATES PATENT OFFICE.

DARIUS E. SHRAUGER, OF ATLANTIC, IOWA.

SHEET-METAL VENTILATION-WINDOW.

1,221,612.

Specification of Letters Patent.

Patented Apr. 3, 1917.

Application filed August 11, 1916. Serial No. 114,402.

To all whom it may concern:

Be it known that I, DARIUS E. SHRAUGER, a citizen of the United States of America, residing at Atlantic, in the county of Cass 5 and State of Iowa, have invented certain new and useful Improvements in Sheet-Metal Ventilation-Windows, of which the following is a specification.

My invention relates to windows in which 10 the frames, adapted to be set permanently in the walls of buildings, and the openable and detached sash closures therefor are both made of sheet-metal; and the objects of my improvement are, first, to provide means for 15 setting the sash partially opened for ventilation, and still preserve the storm-proof features of the closed windows; second, to afford facilities for opening the window at both top and bottom simultaneously and retaining it thus opened; third, to facilitate 20 the adjustment of size of such partial openings; and fourth, to safely and conveniently dispose of detached glazed sash during a period of fully opened window. The above 25 mentioned objects with others hereinafter more fully disclosed are attained by the structure and mechanism illustrated in the accompanying drawing, in which—

Figure 1 is an outside elevation showing 30 the glazed sash closed; Fig. 2, an inside elevation with the parts in the same position as in Fig. 1; Fig. 3, a vertical section through the closed window and portions of 35 the wall above and below showing in broken lines the disposition of the glazed sash when the window is fully opened; Fig. 4, a plan or horizontal section of the closed window and adjacent wall at each side in which the 40 frame is set, taken on the broken line 4—4 of Fig. 3; and Fig. 5, is a fragmental vertical section showing the disposition of the glazed sash when the window is partly opened both top and bottom, in all of which views the 45 same reference numerals refer to the same parts of the mechanism or structure.

The soffit or head 7, is composed of a 50 single strip of sheet-metal and has an intermediate longitudinal portion bent downwardly upon itself to form the head stop 6. An outer edge portion is bent to stand upwardly and serve as the head casing 8.

The jambs 4 have each an intermediate 55 vertical portion bent inwardly upon itself to form the stops 5 and 5 coinciding with

and mitered at their top ends with the ends of the head stop 6. These stops are not continued to the foot of the jambs; the jamb-sheets below being split and lapped to take up the excess of width below the lower end 60 of the stop; the space below the lower ends of the stops accommodate the ends of the outwardly-inclined lip 12 of the bottom rail of the sash, as shown in Figs. 1 and 3. Outer edge portions are bent outwardly, into a 65 plane agreeing with the outside face of the wall, to form the side casings 8 and 8 having their top ends disposed back of the ends of the head casing, as indicated by dotted lines in Fig. 1, and shown in Fig. 2.

Integral triangular extensions of the inner 70 edges of the jambs form the cheeks 18, standing inwardly from the inner face of the wall, as shown in Figs. 3 and 4. The lower longer 75 edges of these extensions are bent to form the stiffening flanges 19 and 19, having their inner projecting portions doubled upon themselves for greater strength and smoothness. A cross-bar 20, of sheet-metal doubled upon itself in cross-section, has its opposite 80 ends fastened to the top ends of the flange. The triangular extensions and cross-bar form a rack or holder for the opened sash, as will be hereinafter further described.

The sill of the frame is made of an 85 integral strip of sheet-metal having an intermediate portion adjacent to its inner edge bent upwardly to form the longitudinal upstanding angular ridge 9, to properly 90 weather the sill. A front edge portion is bent downwardly to a coincident plane with the side casings, to which its ends are fastened, as are the other portions of the sill-ends also fastened to the jambs, in the usual 95 manner.

The bottom rail of the sash, composed of a single strip of sheet-metal, has an intermediate portion bent upon itself to form the longitudinal upstanding flange 10, of double 100 thickness, to back the bottom ends of the panes of glass. An adjacent parallel portion is bent upon itself to form the inwardly and downwardly inclined lip 11. The adjacent opposite edge portions of the strip are 105 bent to close flatly against each other, in an outwardly-standing base 29 beneath the lower edges of the panes,—which stand thereon,—and are then bent to terminate in the double lip 12 inclined outwardly and 110

downwardly, to close onto the frame sill in front of the weather-angle 9, as shown in Fig. 3.

The stiles and munnion are substantially alike in structure; each is composed of a single strip of sheet-metal. A central longitudinal portion of the strip is bent equally upon itself from both edges, to form the inner double flanges 13 of double thickness. 5 Adjacent opposite side portions are bent to stand outwardly at right angles to and centrally of the inner flanges and closed flatly against each other to form a connecting web 30. And the remaining edge portions of the 10 strip are bent apart to form the outer flanges 14, standing oppositely in the same plane; they are thus spaced away from the inner flanges, by the web portion, to form at both 15 sides, of munnion or stile, grooves to receive 20 the edges of the panes of glass. In the stiles the outer grooves could receive the springs, chains or cords for connecting weights or 25 sash balances of sliding windows. The inner fold of the inner flanges of the munnion is 30 extended below the other members, is bent flatwise to conform to the inner surface of the bottom rail and a portion of the lower end bent to stand inwardly to form the horizontal sash lift or handle 16.

35 A top or head-bar 17 is made of doubled sheet-metal, a strip bent laterally upon itself and fastened across the inner face of the top ends of the stiles and munnion. This completes the sash members, leaving the 40 grooves open at the top ends for the insertion of the glass panes. A corner 15 of the top end of the single flange, is bent in above the glass to retain it in the sash. The sash members, like those of the frame, are joined by mitering, interlapping, riveting and 45 soldering in the usual manner.

The inclined lips of the sash bottom-rail form an angular groove adapted to straddle the weather-angle 9, of the sill, thereby pivoting the sash at the bottom, to allow the top to swing inwardly against the flanges 19 of the cheeks, or to close outwardly against the stops 5 and 6. Latch-buttons, 50 each consisting of a latch end 22 and an inwardly inclined thumb flange 23, are pivoted intermediately near the top and on the backs of the stiles. Radial slots 21 through the cheeks receive the outwardly swung latch ends to set the inwardly swung top 55 of the sash at a desired position for top ventilation. When these buttons are turned vertically, as indicated by the dotted lines 24 in Fig. 2, the inclined thumb flanges 23 are adapted to hook over the cross-bar 20, 60 to support the inwardly swung and upwardly slid sash for both top and bottom ventilation, as shown in Fig. 5. For smaller open spaces, both top and bottom, the headed pins 26 are set in selected perforations 65 25 in the lower ends of the flanges 19 of

the cheeks and the latch-ends of the buttons reversed or swung downwardly and outwardly will engage any desired slot to adjust the top opening. For full opening, the sash is drawn upwardly entirely out of the 70 frame, the groove of the bottom rail is seated on the cross-bar 20, and the top of the sash, inclined against the wall above the frame, is secured by the bent button 28, as shown and indicated by dotted lines in 75 Fig. 3.

I claim:

1. In a sheet-metal ventilation window, a sill composed of a single strip having a portion bent to form an upstanding weathering ridge, and jambs each made of a strip having an intermediate longitudinal portion bent upon itself to form a sash-stop the lower end of which is spaced upwardly from the weathering ridge of said sill, in combination with a detached rocking sash, and a sash bottom rail composed of a strip bent upon itself in cross-section to form an inwardly and downwardly inclined longitudinal lip and an outwardly and downwardly inclined lip spaced therefrom to form a longitudinal groove adapted to straddle the weathering ridge of the sill in the spaces below the lower ends of said stops. 80 85

2. In a sheet-metal ventilation window, a sill consisting of a single strip having a portion bent to form an angular upstanding longitudinal ridge to weather the sill, jambs having intermediate portions bent upon themselves to form sash stops, inwardly-disposed extensions on the inner edges of the jambs, and a bar fastened across the space between said extensions, in combination with a sash having a longitudinal groove in its bottom rail adapted to straddle the ridge of the sill and rock thereon to pivot the sash to swing back and forth between said stops and said cross-bar. 90 100 105

3. In a sheet-metal ventilation window, a sill having a longitudinal upstanding weathering ridge, and jamb-extensions to form inwardly standing cheeks having radially disposed slots, in combination with a sash having a longitudinally-grooved bottom rail to straddle the weathering ridge of the sill to pivot the sash at the bottom, and latch-buttons pivoted on the sash to engage the slots in the cheeks. 110 115

4. In a sheet-metal ventilation window, triangular cheeks disposed inwardly from the jambs, flanges on the lower inner edges of the cheeks to stiffen them and form sash stops, and a cross-bar fastened to span the space between the cheeks, in combination with a detached sash, fitted for insertion between the cheeks, and a hook on the back of the sash to engage the cross-bar. 120 125

5. In a sheet-metal ventilation window, a sill having an upstanding weather ridge, jambs having sash stops, triangular cheeks 130

disposed inwardly in the planes of the jambs and having radial slots, and perforated flanges bent on the lower inner edges of the cheeks to stand under the space there-between, in combination with a detached sash having a groove to pivotally seat it on the weather-ridge on the sill or at different heights on pins selectively seated in the perforations of said flanges, and latches on

10 the sash to engage the radial slots.

6. In a sheet-metal ventilation window, a sill having an upstanding weather ridge, suitable jambs and head connected, angular cheeks disposed inwardly from the jambs, and a cross-bar fastened across the space between the cheeks, in combination with a detached sash having in its bottom rail a groove adapted to pivotally engage the weather ridge of the sill and to seat on said 20 cross-bar, and suitable means to fasten the top of the sash against the wall above when seated on said cross-bar.

7. A ventilation window, comprising a

sill having an upstanding weathering ridge, jambs, vertical sash stops on said jambs 25 having their lower ends spaced above the ends of said weathering ridge, a sash adapted to close outwardly against said stops, and an outwardly and downwardly inclined lip on the sash adapted to stand through 30 the spaces between the lower ends of said stops and the ends of said ridge and overlap the ridge throughout its length.

8. A ventilation window, comprising a window sill having an upstanding weather- 35 ing ridge, cheeks extended inwardly on the planes of the window jambs, a detachable sash having a longitudinal groove in its bottom rail adapted to engage said weathering ridge to pivot the sash, and inclined 40 flanges on said cheeks to guide the grooved rail onto said ridge and to limit the inward swing of the sash.

In testimony whereof I have affixed here-to my signature.

DARIUS E. SHRAUGER.
